Hal C. Mettler, 680 Westbridge Place,
Pasadena, Calif. 91105

Filed Nov. 1, 1968, Ser. No. 14,269

Term of patent 14 years

Int. Cl. D24—02

U.S. Cl. D83—1

FIG. 1 is a perspective view of a short wave diathermy unit, showing my new design; and

FIG. 2 is a perspective view, as seen from the opposite side of FIG. 1.

The dominant features of my new design are shown in solid lines in the drawing. The meter on the top of the center post is diagonally shaded to indicate transparency.

I claim:

The ornamental design for a short wave diathermy, as shown and described.
